DESIGN FOR A CORNER CHINA CLOSET

Application filed June 10, 1929. Serial No. 31,625. Term of patent 14 years.

To all whom it may concern:

Be it known that we, GEORGE A. SIMONS and GEORGE FREEBERG, citizens of the United States, residing at Minneapolis, county of Hennepin, and State of Minnesota, have invented a new, original, and ornamental Design for a Corner China Closet, of which the following is a specification, reference being had to the accompanying drawing, forming part thereof.

Figure 1 is a front elevational view of a corner china closet, showing our new design; and Figure 2 is a cross sectional view taken on line 2—2 of Figure 1.

We claim:

The ornamental design for a corner china closet as shown.

GEORGE A. SIMONS.
GEORGE FREEBERG.
